UNITED STATES PATENT OFFICE.

LEENDERT JANSE, OF THE HAGUE, NETHERLANDS.

SLIDING DOOR.

1,223,697.

Specification of Letters Patent. Patented Apr. 24, 1917.

Application filed March 23, 1915. Serial No. 16,403.

To all whom it may concern:

Be it known that I, LEENDERT JANSE, a subject of the Queen of the Netherlands, and residing at 53 Kanaalweg, The Hague, the 5 Netherlands, have invented a certain new and useful Sliding Door, of which the following is a specification.

This invention relates to a new system of sliding door and has for its object to provide a door of simple construction which can readily and quickly be opened and closed.

The sliding door constructed in accordance with this invention is especially useful for railway wagons, but it may also be applied to steamers, lift cages, buildings and the like, as will be readily understood from the following detailed description.

On the accompanying drawing one form of a sliding door according to this invention 20 as applied to a cattle wagon is illustrated.

Figure 1 is an elevation of the closed door mounted in the end of the wagon, the latter being shown in section on line 1—1 in Fig. 2.

Fig. 2 is a plan view of the same with the 25 end of the wagon shown in section on line 2—2 in Fig. 1.

Fig. 3 is an elevation of the opened door with the end of the wagon shown in section on line 3—3 of Fig. 4.

Fig. 4 is a plan view of the same with the 30 end of the wagon shown in section line 4—4 in Fig. 3.

Like letters indicate like parts throughout the drawing.

The door 1 is suspended from or supported by two hooks 2 and 3, which are pivotally mounted respectively in brackets 4 and 5, rigidly attached to the upper part of the door. At their upper extremities the hooks 40 2 and 3 are provided with rollers 6 and 7 respectively; said rollers running on guide rails 8 and 9 arranged at a right angle to one another. In the floor of the wagon two guides 10 and 11 are provided respectively arranged parallel to and in a vertical direction under the guide rails 8 and 9. The guide pins 12 and 13 arranged in a vertical direction under the hooks 2 and 3 respectively can slide in the guides 10 and 11.

The door 1 may be constructed of wood, 50 steel or any other suitable material. In the closed position of the door (as shown in Figs. 1 and 2), the roller 6 is situated on the guide rail 8 near the intersecting point of the guide rails 8 and 9 and the roller 7 on the guide rail 9 at some distance from said

intersecting point. The guide pins 12 and 13 are correspondingly situated in the guides 10 and 11 respectively.

In opening the door the roller 6 runs over 60 the rail 8 and the roller 7 over the rail 9; in a corresponding manner the guide pins 12 and 13 slide in the guides 10 and 11 respectively. During this movement of the door the hooks 2 and 3 pivot in their brackets 4 and 5 and each part of the door describes an elliptic curve. In the fully opened position of the door (as shown in Figs. 3 and 4) the roller 6 is situated on the rail 8 near the end thereof opposite to the intersecting point of 70 the rails 8 and 9 and the roller 7 on the rail 9 close to said intersecting point. The guide pins 12 and 13 again occupy corresponding positions in the guides 10 and 11 respectively.

The doors according to this invention present considerable advantages on account of the little space occupied thereby and the readiness with which they may be opened and closed in loading and unloading wagons. 80 It is a particular advantage of this sliding door that it can readily be provided at the front and rear ends of wagons and cars, and when in the open position it projects from the end of the wagon (as shown in Figs. 85 3 and 4) thus acting as a guard for cattle or persons passing from one wagon to the next.

It will be understood that the sliding door as described and illustrated may be modified in several ways in order to make 90 it better suit the particular uses for which it is destined without departing from the spirit of the invention. For instance, the door may consist of two parts moving in opposite directions in opening the door. Further the top guide rails, and the bottom guides, do not necessarily form a right angle with each other. The upper part of the door may be guided by pins in suitable guides, the lower part then being provided with 100 rollers running in corresponding rails.

Having now described my invention what I claim as new and desire to secure by Letters Patent is:—

1. In a railway wagon the combination 105 of a vertical door member, a side horizontal supporting track arranged substantially parallel to the side wall of the wagon, an end horizontal supporting track arranged substantially parallel to the end wall of the 110 wagon, a pair of spaced brackets attached to said door member, means for engaging

said side track only and pivotally mounted on a vertical axis on one of said brackets, means for engaging said end track only and pivotally mounted on a vertical axis on the 5 other bracket, a pair of guide tracks and a pair of guide members attached to said door member and each engaging in one of said guide tracks, said end-supporting track being at a smaller distance from the end wall 10 of the wagon than it is from the adjacent vertical edge of the door member when the latter is in its open position whereby the door member protrudes from the end of the wagon when in said position.

15 2. In a railway wagon the combination of a vertical door member, a side horizontal supporting rail arranged substantially parallel to the side wall of the wagon, an end horizontal supporting rail arranged sub- 20 stantially parallel to the end wall of the wagon, a pair of spaced brackets attached to said door member, a roller for engaging said side rail only and pivotally connected to one of said brackets on a vertical axis, a 25 roller for engaging the end rail only and pivotally connected to the other bracket on a vertical axis, a pair of guide tracks arranged in vertical alinement with said supporting rails, and a pair of guide members attached to said door member and each en- 30 gaging in one of said guide tracks, said end supporting rail being at a smaller distance from the end wall of the wagon than it is from the adjacent vertical edge of the 35 door member when the latter is in its open

position whereby the door member pro- trudes from the end of the wagon when in said position.

3. In a railway wagon the combination of a vertical door member, a side horizontal 40 supporting track arranged substantially parallel to the side wall of the wagon, an end horizontal supporting track arranged substantially parallel to the end wall of the wagon, a pair of spaced brackets, at- 45 attached to said door member, means for engaging said side track only and pivotally mounted on a vertical axis on one of said brackets, means for engaging said end track only and pivotally mounted on a vertical 50 axis on the other bracket at a lesser distance from the door member than the aforesaid axis, a pair of guide tracks, and a pair of guide members attached to said door mem- 55 ber and each engaging in one of said guide tracks, said end supporting track being at a smaller distance from the end wall of the wagon than it is from the adjacent vertical edge of the door member when the latter is in its open position whereby the door mem- 60 ber protrudes from the end of the wagon when in said position.

In testimony whereof I have signed my name to this specification in the presence of two subscribing witnesses.

LEENDERT JANSE.
